UNITED STATES PATENT OFFICE.

THOMAS H. STAGG, OF COLUMBUS, OHIO, ASSIGNOR TO THE KILBOURNE AND JACOBS MANUFACTURING COMPANY, OF COLUMBUS, OHIO, A CORPORATION OF OHIO.

DUMP-CAR.

No. 921,300.

Specification of Letters Patent. Patented May 11, 1909.

Application filed March 13, 1908. Serial No. 420,992.

To all whom it may concern:

Be it known that I, THOMAS H. STAGG, a citizen of the United States, residing at Columbus, in the county of Franklin and the 5 State of Ohio, have invented certain new and useful Improvements in Dump-Cars, of which the following is a specification.

My invention relates to improvements in dump cars and has especial relation to the 10 means for holding the door on the lowered or dumped side of the car in elevated position while the car bed or body is carried to its dumped position, whereby the lading is permitted to be discharged; it comprises essentially an arm depending loosely from the car, a guide for said arm, and a member against which the arm may engage at its lower ends to prevent its further downward movement, whereby the door structure is held aloft.

20 It is not contemplated that the arm member should be attached except adjacent to its upper end, and being pivoted to swing freely and to play loosely in the guide member, it is always properly positioned to be actuated to 25 perform the function of holding the car door aloft when the car body or bed is given a dumping movement.

In the drawings which are hereto attached and are hereby made a part of this specification, Figure 1 is an end view of a car having 30 my improvements thereon, the positions of the various parts when the car bed is dumped being shown in dotted lines; Fig. 2 is a side elevation of my improvements in place on a 35 car.

Referring to the drawings in which the same numeral designates the same part throughout, 1 is a car bed pivoted at 2 to swing laterally, and provided with side doors 40 3 and 4 hinged at 5 and 6 respectively to the arms 7 and 8 respectively, the latter being pivoted supported on the car body 1 at 9 and 10 respectively. The gusset plate 11 is mounted upon the arm 8 to hold the door 4 45 in proper position when opened to return to certain locking engagement with the hook 12 when the car bed is again righted, as may be seen in Fig. 1.

Pivoted at 13 to the arm 8 is the depending 50 arm or member 14 having its lower end free or unattached; a swinging casing or sleeve or guide member 15 is mounted upon the car understructure at 16, and therethrough is inserted the arm 14. Also mounted pivotally 55 at 16 is a stirrup or stop member 17 whose

position is determined by that of the guide member by being carried thereby as shown in Fig. 1 on the left when the arm 14 is operated to maintain the door in elevated position; this is accomplished by the pin 17^a on the 60 guide or sleeve 15, which carries the stirrup with the guide when the lower end of the guide is swung toward the center of the car, which takes place on the side of the car on which the lading is dumped, but on the opposite side of the car the position of the stirrup or stop member is undisturbed. This stirrup 17 is therefore always in position to receive the lower end of the arm 14 to support the same whereby the door is prevented from 70 traveling downwardly with the car bed when the latter is dumped.

If the car bed be dumped toward the left as indicated in Fig. 1, the parts will assume the positions indicated by the dotted lines, 75 the guide member 15 not being shown in its rotated position to avoid confusion due to numerous dotted lines. However its direction of movement and the position it would assume may readily be understood, especially 80 by reference to the guide member 18 on the opposite side of the car. When the arm 14, moving with the car, engages the stirrup 17 with its lower end, said arm is prevented from moving farther down, and as the tilting 85 movement of the car bed continues, the door 4 is held aloft in the manner shown in dotted lines in Fig. 1. The lading is now free to discharge from the car bed. Upon righting the car, the bed is moved upwardly until it 90 engages the door 4 and carries it along thereby causing the arm 14 to be withdrawn from contact with the stirrup 17, and causing the sleeve to be swung back to its normal position.

95 The arm 14 is seen to have connection with the door at one of its ends and to move therewith, while its other end is free; joints or hinges in the arm 14 are completely avoided, and the construction is composed of very 100 few parts of great simplicity, which are not likely to get out of order in use.

What I claim is:

1. In a dump car having a swinging door construction thereon, a member pivotally connected therewith at one of its ends and having its other end free, a pivoted guide for said member and a stop pivotally associated with said guide and arranged to move with the guide to lie in the path of said member 110.

whereby said door is maintained in an elevated position on the side toward which the car is dumped.

2. In a dump car having a swinging door construction, an arm pivotally mounted thereon at one end and having its other end free, a swinging guide for said arm, and a swinging stop member to limit the downward travel of said member.
- 10 3. In a dump car having a swinging door construction, an arm pivotally mounted thereon at one end and having its other end free, a swinging guide for said arm, and a swinging stop member to limit the downward travel of said member, as said car is dumped, whereby said door is maintained in elevated position.

4. In a dump car having a swinging door construction, an arm pivotally connected therewith at one end and having its other end free, a sleeve member open at both ends adapted to receive said arm to guide the same, and a stop member arranged to be engaged by the free end of said arm to limit the downward movement of said arm, whereby said door is maintained in elevated position as the car is dumped. 20 25

In testimony whereof I affix my signature in the presence of two witnesses.

THOMAS H. STAGG.
